Attorneys

UNITED STATES PATENT OFFICE.

RICHARD W. SHAFFER, OF EBENSBURG, PENNSYLVANIA.

BRACE.

Application filed March 13, 1922. Serial No. 543,505.

To all whom it may concern:

Be it known that I, RICHARD W. SHAFFER, citizen of the United States, residing at Ebensburg, State of Pennsylvania, have invented certain new and useful Improvements in Braces, of which the following is a specification.

The invention relates to improvements in a body brace.

10 It is an object of the invention to provide a brace which is particularly adapted for attachment to the shoulder for strengthening or supporting the humerus, elbow and forearm, although the brace is of a structure that 15 could be applied to other portions of the body.

The present invention is based on the discovery that where a brace is constructed with a portion engaging the shoulder and with 20 connected portions which may be strapped around the humerus, and also if desirable around the arm below the elbow, that said brace will serve to support the arm so that the same can be moved freely even though 25 portions of the bone have been removed. The invention is particularly adapted as a brace for the arm where sections of the bone have been severely weakened or removed from gun-shot wounds or the like, and is 30 one wherein the user may freely shift his arm from place to place which would otherwise be a physical impossibility.

In the accompanying drawings I have shown the preferred form of my brace, but 35 the same is susceptible of many structural changes without departing from the spirit of my invention.

In the drawings, Figure 1 represents a 40 perspective view showing the brace in use. Figure 2 is a vertical sectional view. Figure 3 is a perspective view showing the brace in use with the forearm portion removed. Figure 4 is a vertical section of upper portion and shoulder pad; and Figure 5 is a 45 transverse section on line 5—5 of Figure 4.

Referring now more particularly to the drawings, wherein like reference characters indicate corresponding parts, the numeral 1 designates a shoulder pad which is adapted 50 to seat upon the top of the shoulder and is provided with fastening straps 2 and 3 by which the pad is firmly united to the shoulder. Mounted upon this pad is a bracket 4 with which a curved arm 5 is 55 swivelly connected with the bracket by means of a ball head 6 entering a keeper 7

on the bracket. This arm is capable of a material movement, and serves to support a humerus pad 9 which will be later described. The arm 5 near its lower end is 60 threaded at the point 6 receiving a turnbuckle 7, the other end of which turnbuckle engages a rod 8 that is connected with the humerus pad and is also threaded by which the humerus pad may be adjusted. This 65 humerus pad is preferably composed of leather, is lined with felt, or the like, and is strapped or laced to the body of the user by lacings 10. Straps 11 also project from the shoulder pad which may be connected by 70 means of the buckles 12 with the other end of the humerus pad to assist in holding said pad in position. When a portion of the humerus is shot away the addition of this 75 pad will so strengthen the arm that the entire arm can be freely moved, as though the bone were intact. The pad is quite tightly fastened to the arm for obvious reasons. The rod 8 is preferably riveted to the pad, and at its lower end is provided with a 80 threaded interior socket 13 for a purpose which will later appear.

Should the arm be injured above the elbow or in the forearm rather than the humerus, or if both the humerus or elbow or 85 forearm are injured, I then couple with the rod 8 a bar member 14, which is threaded in the socketed end 13 of the rod 8, the bar member having an intermediate hinged joint 15 and an extended part 16 which is riveted 90 to a forearm brace 17, which brace is preferably composed of leather and tightened around the forearm by lacings or the like. When this forearm brace is used I also provide a second bar 18 which is similar in construction to the bar 14 except that said bar 95 is preferably detachably united to the humerus pad by the fastening elements 19 for the purpose of giving support to both sides of the forearm pad so as to support with 100 much strength that portion of the arm. It will be appreciated that the forearm pad 18, together with its supporting bars may be removed from the humerus pad if desirable, this of course depending upon the part of 105 the arm that is weak or has suffered injury.

I have discovered that in cases where a large part of the shoulder bone or humerus has been removed as the result of injury that the application of the brace with the 110 shoulder and humerus pads alone, will so support or strengthen the arm that the same

can be lifted and freely removed, which movement would otherwise be impossible. Likewise when the forearm has been injured or the elbow weakened the addition of the 5 forearm pad connected with the humerus pad so supports that portion of the arm that the same can be freely moved with great ease and without suffering.

Having thus described my invention, what 10 I claim is:

1. A brace of the character described, comprising a shoulder portion adapted to be clamped upon the shoulder, a pivoted arm connected with the shoulder portion, and a 15 humerus pad adapted to be fitted around the arm below the shoulder connected with said arm projecting from the shoulder pad.
2. A brace of the character described, comprising a shoulder portion adapted to be clamped upon the shoulder, a pivoted arm connected with the shoulder portion, and a humerus pad adapted to be fitted around 20 the arm below the shoulder connected with said arm projecting from the shoulder pad, extensions connected with the humerus pad and a forearm pad carried by said extensions, said extensions being hinged intermediate their ends.
3. The combination with a shoulder pad 30 adapted to be applied to overlie the shoulder of the body, and means for uniting said pad to the shoulder, a hinged arm of substantially rigid material pivotally connected with said shoulder pad above the shoulder 35 of the wearer, and a humerus pad adapted to be strapped around the arm.
4. The combination with a shoulder pad adapted to be mounted over the shoulder of

a body, and means for uniting said pad to the shoulder, a depending arm of rigid material pivotally connected with the shoulder pad, a humerus pad below the shoulder united to said arm, a pair of hinged bars united to the humerus pad, and a forearm pad 40 connected to said bars. 45

5. The combination with a shoulder pad adapted to fit over a shoulder, means for attaching said pad to the shoulder, an arm pivotally mounted on said pad above the shoulder, said arm having a downwardly extending portion normally projecting beyond the shoulder, a pad adapted to be attached to the human arm carried by said depending arm. 50

6. The combination with a shoulder pad 55 adapted to fit over a shoulder, means for attaching said pad to the shoulder, an arm pivotally mounted on said pad above the shoulder, said arm having a downwardly extending portion normally projecting beyond 60 the shoulder, a pad adapted to be attached to the human arm carried by said depending arm, extensions connected with said depending arm, and a forearm pad united to said extensions. 65

7. The combination with a shoulder pad adapted to be tightly clamped over the shoulder, of a supporting element having a relatively straight portion and a curved upper end pivotally mounted above the 70 shoulder to said pad, and an arm engaging pad adapted to be carried by said relatively straight portion of said supporting member.

In testimony whereof I affix my signature.
RICHARD W. SHAFFER.
